BUTTON FEEDING ATTACHMENT

William R. McDaniel, Englewood, Tenn.

Application July 3, 1945, Serial No. 603,009

7 Claims. (Cl. 112—113)

1

This invention relates to sewing machines and more particularly to a button feeding attachment for sewing machines.

In the machine sewing of buttons, it is important, for speed and accuracy, that the buttons be fed right-side-up and that they be positioned for sewing so that, when sewn, no button of a row of sewn buttons is out of line.

An important object of the invention is to provide a button feeder which will accurately feed buttons right-side-up, rapidly and without hand manipulation of the buttons.

Another important object is to provide a button sewing attachment, having means to manipulate the button so that, no matter if it has four eyes, instead of two, it will be accurately positioned and will not be out of line with respect to the other buttons of its row.

Still another important object is to provide a hopper-feed button sewing attachment, the hopper of which may be readily inverted, in order to quickly empty it, as when changing to another color or style of button.

Other objects and advantages of the invention will be apparent in this specification, taken in connection with the accompanying drawings forming a part of this specification, and in which drawings:

Figure 1 is a front elevation of a machine to which the novel button feeder is attached.

Figure 2 is an end view thereof, at the drive means end of the machine.

Figure 3 is a top plan of a portion of the attachment, removed from the machine.

Figure 4 is a vertical longitudinal section upon substantially the line 4—4 of Fig. 3.

Figures 5 and 6 are vertical transverse sections upon substantially their respective lines of Fig. 4.

Figures 7 to 12 inclusive are views of various portions of the operating means of the button feeder; Figure 7 being a vertical longitudinal section of a clutch assembly; Figure 8 a plan view of an operating link associated therewith and carrying a clutch-operating wedge; Figure 9 a plan view of a rotating disc, connected with the link; Figure 10 a plan view of a cam-surfaced disc engaged by the wedge; Figure 11 is a longitudinal section through mechanism operatively connecting the means of Figures 7 to 10 inclusive with the mechanism of Figures 13 to 24 inclusive, and Figure 12 is a view, partly in section of a support for the mechanism of Figure 11.

Figures 13 to 24 are views of various portions of the button positioning and hold down means, operated by the drive means of Figures 3 and 7 to 55

2

11, and dependent upon the feeding devices of Figures 4, 5 and 6; Figure 13 being substantially on the line 13—13 of Figure 3; Figure 14 a top plan of a portion of the means of Figure 13; Figure 15, a view somewhat like Figure 13 but showing a different position of some parts; Figures 16 and 17 front elevations of a button holder in two positions; Figure 18 an end elevation of the button holder; Figure 19 a perspective view of a portion of the button holder; Figures 20 to 23 inclusive, are front elevations of portions of the holder of Figures 16 and 17; and Figure 24 a fragmentary perspective view of a portion of the means of Figures 3, 13 and 19, showing their relationship one with another.

In the drawings, wherein for the purpose of illustration is shown a preferred embodiment of the invention and wherein similar reference characters designate corresponding parts throughout the several views, the button sewing machine, generally designated as A, is mounted upon a support B and is operated by a drive means C. A conventional button is shown at D, while the novel button feeding attachment is designated as E and comprises a button hopper 20, means 21 to deliver buttons, right-side-up, from the hopper 20 to a button positioning and hold down means 22, and a power take off 23 from the drive means C to the hopper 20 and to the means 21.

The button sewing machine A is of conventional construction including a somewhat L-shaped hollow bracket 25, supporting or enclosing much of the sewing mechanism 26 of the sewing machine 35 for cooperating with a hollow work-support, 27 carrying the remainder of the sewing mechanism 26. The bracket 25 carries a driven pulley 28 secured to a drive shaft (not shown) within the bracket 25, which drive shaft is operatively connected with the needle 29 of the sewing mechanism, for vertical reciprocation of the needle. This bracket 25 also pivotally supports a conventional lift lever 30. Carried by the work support 27 is a conventional shuttle (not shown) being part of the sewing mechanism 26.

Carrying the machine A is a suitable conventional support B, which may also carry the drive means C. The latter may include an ordinary electric motor 35 having a drive pulley 36 about which is a belt 37 and which belt 37 extends to and about the driven pulley 28. The support B may also carry a foot pedal 38 with an upwardly-extending link 39 therefrom operatively connected to adjacent one end 40 of the lift lever 30.

A conventional button D, is shown by way of

illustration, having an upper or outer flat face 42, a convex under face 43 and four holes or eyes 44 extending from face to face.

Now, as for the novel button feeding attachment E. The button hopper 20 thereof, shown more particularly in Figures 3 and 4 is, preferably, a cup-shaped container having an upwardly opening mouth 45 and a restricted exit 46 opening into a downwardly and forwardly extending, substantially J-shaped button passageway 47, the walls 48 and 49 of which may be mostly circular in transverse cross section. However, while the walls 48 nearest the hopper and preferably integral therewith, are stationary, the walls 49 rotate and thus provide for a much better feed movement of the buttons than if the walls 48 and 49 were both stationary. The end of the wall 48, farthest from the hopper 20 is provided with a flange 50, which cooperates with a flange 51, carried at one end of a circular gear-accommodating housing 52 disposed about the peripheral portion of one end 53 of the wall 49. Carried by this peripheral portion are radially extending gear teeth 54 which mesh with the teeth of a worm gear 55, also carried in the housing 52, with its axis of rotation normal to that of the axis of rotation of the wall 49. Any suitable means may be provided to detachably couple the flanges 50 and 51 together, as by the screws 56, extending into screw threaded openings in these flanges. The housing 52 is provided with a tubular extension 57 accommodating a short shaft 58 carrying the worm gear 55 and the end portion of a shaft 59, the two shafts being detachably coupled together, as by a splined connection within the extension 57. The free end of the extension 57 is provided with exterior screw threads to cooperate with a nut 61 and about the extension 57 is the tubular portion of a bracket 62 secured as will be subsequently described.

The means 21 to deliver buttons, right-side-up, from the hopper 20 to the button positioning and hold down means 22, includes the outwardly flaring open end portion 65 of the rotating wall 49. This portion 65 is provided with a plurality of spaced apart depressions or concavities 66 and, between each two concavities 66, is a spacer section 67. Contacting the outer faces of the spacer sections 67 and secured thereto is a circular cover plate or disc 68. This may be secured to the spacer sections 67 by screws 69. With this construction of flared end portion 65, concavities 66 therein, spacer sections 67 and cover plate 68 there is provided a number of slots leading from the button passageway 47 to exterior of the walls 48 and 49. The concavities 66 are not circular but more in the nature of slots, so that buttons D may slide over the concave faces of the concavities from the passageway 47 outwardly, by gravity, as the structure rotates. But the buttons D may enter the concavities 66 only in one position i. e., with their upper (outer) flat faces 42 facing the cover plate 68, for only if they are so positioned will they be able to enter the concavities, since the convex faces 43 of the buttons will slide over the concavities 66, but the latter will not accommodate the flat faces 42.

Associated with the assembly just described and forming another portion of the means 21, is a right-side-up button-receiving chute structure 70, which also serves as a bearing for the rotating assembly last described since it supports the bracket 62. This structure 70 includes a U-shaped portion 71 which may be provided with a pair of perforated ears 72 for attachment to the sew-

ing machine bracket 25 as by screws. One arm 73 of the U-shaped portion 71 (in the event the wall 49 rotates clockwise as shown) is provided with a button passageway 74 so disposed, as shown in Figure 5, that a button will drop, by gravity, into it from a concavity 66, cannot turn over, and will slide downwardly to a discharge mouth 75.

From the discharge mouth 75 an open chute or way 80 conducts the buttons, by gravity, to the button positioning and hold down means 22. This chute 80 has side flanges 81 to confine the buttons and, associated with the chute 80 is a circular rotating brush 82, the bristles of which are adapted to contact the buttons lightly and urge them downwardly and prevent jamming of the chute. This brush 82 is so positioned that its axis of rotation extends across the chute 80 and its bristles may enter the chute but will clear the means 22.

The button positioning and hold down means 22, is operatively connected with the lift lever 30 and the power take off means 23, as may be seen particularly in Figures 1, 3 and 7 to 11 inclusive.

First, referring to one connection with the lift lever 30. This includes a depending arm 85, pivotally connected at its upper end with the lift lever 30 and provided, at adjacent its lower end, with a longitudinally-extending slot 86 into which extends a connection pin 87. This pin also extends into an arcuate slot 88 in a rotating disc 89. For convenience the pin 87 may be the shank of a bolt, with its head adapted to prevent the bolt from moving out of the arcuate slot 88 in one direction, and a nut on the end of the shank, 35 outwardly of the arm 85, preventing movement in the other direction. The arm 85 is so weighted that it never occupies a position at dead center with respect to the arcuate slot 88. This is effected by providing a wedge member 89' which 40 is adjustably carried at the inner side of the arm 85. The member 89' extends slightly more beyond one vertical edge (the left hand edge in Figure 8) of the arm 85 than beyond the other vertical edge of the arm 85. This is effected by 45 providing a second longitudinally extending slot 90 therein intermediate the ends of the arm and several perforations in the bracket portion 91 of the wedge member, these being disposed to one 50 side of the longitudinal medial line of the bracket portion 91 with adjustment bolts 92 extending through the second slot 90 and the perforations, 55 nuts being screwed upon the shanks of the bolts 92. This wedge member 89', which has one flat face 93 and a bevelled or sloping face 94, in addition to the function mentioned, also effects operation of a clutch assembly 95 next to be described.

The clutch assembly 95 includes a pair of co-operating clutch plates 96 and 97, one, 97, fixed to a shaft 98 and the other, 96, slidable toward and away from the plate 97, being urged into engagement with the latter by the descent of the arm 85 carrying the wedge member 89'. A conventional expansion coil spring 99 may be employed to urge the clutch plates apart when the plate 96 is released by the wedge member, associated with a cam to be subsequently described.

As a bearing for the plate 96 engaged by beveled face 94 of the wedge member 89', there is provided a second rotating disc 100, somewhat like the disc 89 but having a hub portion for conventionally keying the plate 96 thereto so that the plate 96 is slidable along the hub, and the disc 96 is not provided with a slot. This disc 100 is spaced from but coupled to the disc 89 in any desired way

as by a coupling pin 101 adjacent the peripheries of the discs.

The bevelled face 94 of the wedge member 89 is adapted to engage the bevelled area 102 of the clutch plate 96. This area 102 extends over only a portion of the face of the plate 96 and constitutes an arc of a circle. Thus, when the foot pedal 38 is depressed, the rod 39 will draw down the end 40 of the lift lever 30, and force the arm 85 downwardly carrying the wedge member 89 with it, and the latter will operate to force the clutch plate 96 into engagement with the clutch plate 97. Of course, the coil spring 99 forces the plate 96 away from the plate 97 when the former is not engaged by the wedge member 89'. The clutch plate 97 being mounted for rotation on the shaft 98 will impart rotation (not a complete rotation of 360° however) to the clutch plate 96 when they are in engagement, and this causes partial rotation of the discs 100 and 89, which movement of the disc 89 causes reciprocation of a link 103, pivoted, adjacent one end to the pin 101 and, adjacent its other end to a pivot 104 carried by a short downwardly-extending crank arm 105 (shown more particularly in Figure 11) fixedly connected to one end of a substantially horizontally-disposed extension 106, and, from adjacent the other end 108 of which is secured a relatively long arm 107. This end 108 of the extension 106 may be screw threaded, with the screw threads thereof loosely cooperating with the screw threads of a socket carried by a small bracket 109 depending from the L-shaped bracket 25 of the machine A. A coil spring 110 about the extension 106 has one end secured to the arm 105 and its other end 111 secured to the bracket 109 as in Figure 12. Rotation of the extension 106 urged by the assembly 85 to 105, in one direction coils the spring 110 and partial uncoiling of this tends to cause rotation of the extension in the other direction when the assembly 85 to 105 itself becomes inoperative.

At its lower end, the long arm 107 extends into a slot 112 in a sliding member 113, shown more particularly in Figure 14, as well as in Figures 11 and 13. Preferably, this sliding member 113 is narrow and elongated and carries, at its upper face, a preferably elongated leaf spring or vibrating member 114, as by being attached, at its inner end 115 to the sliding member 113 by the screw 116 and being free at its opposite end 117, which overhangs the outer end 118 of the sliding member 113. This end 117 may be provided with a slot 119 to receive the neck portion of a button positioning means 120, preferably comprising a head portion 121 overhanging the slot 119, a neck portion 122, accommodated in the slot 119 and a foot or base portion 123 engaging the lower face of the leaf spring 114. Extending downwardly from the lower face of the foot portion 123 are button eye-engaging prongs or pins 124. Extending radially from the head portion 121 are two arms 125 with their axes substantially coincident, and the head portion 121 also carries a small hook 126, extending upwardly. A retraction coil spring 127 plays an important part in the assembly, and extends from the hook 126 to a hook 128, secured to the sliding member 113, which hook 128 extends upwardly through a small slot in the leaf spring 114. This coil spring 127 causes the leaf spring 114 to take, normally, the position shown in Figure 13. It should be noted that the body of the hook 128 has two functions, one, as a support for one end of the

coil spring 127 and, the other, to prevent transverse movement of the leaf spring 114. It is now obvious that, by unhooking the spring from the hook 126, the button positioning means 120 may be removed and a similar means, but with the prongs or pins 124 spaced farther apart, or with more or fewer prongs or pins, substituted. In the example shown in Figures 13, 14 and 15, a four-prong means 120 is contemplated.

10 In addition to normally retaining the leaf spring 114 as described, the coil spring 127 retains the button positioning means against sliding out the slot 119 and assists in oscillation of the latter as will be subsequently described.

15 This sliding member 113 slides in an elongated guideway 130, having upper flanges 131 to retain the sliding member 113 against upward movement. The guideway 130 extends normal to and merges into the lower open end of the chute 80 through which the buttons D slide. Since the guideway is provided with an opening 131' at the mouth of the chute 80, the buttons D will slide from the chute into the guideway. Closely adjacent this chute mouth 131' as may be seen in 20 Figures 13 and 24, the flanges 131 are upwardly arched, as at 132, and the leaf spring 114 provided with a pair of short laterally extending arms 133 so that, as the sliding member 113 is urged forwardly, the arms 133 will slide over these 25 upwardly-arched portions of the flanges 131 and elevate the free forward end 117 of the leaf spring, as shown in dotted lines in Figure 13, but, as the arms 133 leave the upwardly-arched portions, the end 117 will move downwardly again, 30 just as the button positioning means 120 reaches the button D, discharged into the guideway 130 from the chute 80. The prongs 124 will engage the button D and slide it forwardly as the sliding member 113 moves forwardly. At 134 is shown 35 a vertical pin which is momentarily engaged by one arm 125 and oscillates the means 120 and the button so that the prongs 124 will move over the upturned face 42 of the button D and enter the holes thereof. Eventually, forward movement of the sliding member 113 will carry the button D to the position shown in Figure 24 but, 40 just before the button reaches this position, the same will be accurately positioned for sewing, but this will be described in connection with the following detailed description of another portion of 45 the button positioning and hold down means 22. 50 More specifically, the portion to be now described, constitutes the hold down means.

55 Illustrated in Figures 16 to 24 is this hold down means, which includes a substantially vertical support plate 140, shown particularly in Figure 23, rockably supporting a pair of depending legs 141 terminating in button-gripping, facing claws or clamps 142, one being shown particularly 60 in Figure 19 and both in Figures 16 and 17. Intermediate the end of each leg 141 is a cam member 143 extending substantially normal thereto having a cam face 144. Above the clamps 142 is a retraction coil spring 145 extending from 65 one leg to the other and, extending through each clamp body is a set screw 146, so positioned that the free end of its shank points toward the left of the machine A. Since these legs 141 rock, it is apparent that the longitudinal axis of the set 70 screws 146 describe arcs as the legs rock, and the positions of the free ends of these shanks will be, upon certain movements of the legs 141, in positions to be contacted, as the sliding member 113 moves forward, first by one of the radially-extending arms 125 of the button positioning

means 120, and then by the other arm 125 (since the arms are not normally positioned with their longitudinal axis at right angles with the longitudinal axis of the elongated guideway 130). This positions the button D for sewing, since one arm 125 comes to rest against the shank of one set screw 146 so as to position the holes for entrance of the button-sewing needle when the means 120 comes to rest. As the means 120 reaches a position in which the button D is positioned as shown in Figure 24, the means 120 will have come to rest and the button D (and each preceding and following button D) will be positioned with its eyes or holes disposed just like every other button, and the springs 114 and 121 will urge the means 120 upwardly, but the button D will be held, by this time, by the clamps or claws 142, against movement of any kind. Consequently, it will not follow the means 120, which will now move backwardly (or to the left), carried by the sliding assembly (since the arm 107 had reached its farthest movement to the right and commences its movement to the left).

Actuation of the legs 141 is effected by the up and down movement of a substantially vertically-disposed jointed slide or generally wedge-shaped member 148 including an upper wide body portion 149 shown particularly in Figure 20, and a lower, narrow body portion 150, shown particularly in Figure 21, hinged together by a conventional pintle or pin. The body portion 149 slides over the face 151 (shown in Figure 23) of the support plate 140, as may be appreciated from Figures 16 and 17 and is held in position by a centering block 152 which extends across the upper open space 153 of the plate 140 and slidably engages the inner opposite faces of the vertical walls defining this space, for vertical sliding movement. The body portion 149 and block 152 may be secured together as by screws 154. The lower edges 155 of the portion 149 are shaped to substantially the shape of the cam surfaces 144 of the cams 143, and the cams engage these edges 155, as may be seen in Figure 16, when the slide 148 is in one (lower) position. The portion 149 has substantially like side faces 156 to be abutted by the upper inwardly-extending ends 157 of the legs 141 when the slide 148 is in another (upper) position, as in Figure 17.

The body portion 150 is provided with downwardly and inwardly converging side faces 158, terminating in a foot 159, wider than the lower end of the converging-faced section of this portion 150 so that a pair of shoulders 160 and a rounded surface 161 are provided. A leaf spring 162 or the like is fixed to the portion 149 and bearing against the portion 150, to yieldably restrain the portions against folding. However, as the slide 148 moves downwardly from its upper position, the head 159 rides over the cams 143, instead of actuating them, since the spring 162 will yield enough for this and, after the head 159 has descended beyond the cams 143, the former will snap back against the central portion 163 of the support 140. This is effected by slightly beveling the outer surface at the beaks 164 of the cams 143. On the other hand, when the slide 148 ascends, the shoulders 160 will abut the flat lower faces 165 of the cams, adjacent the beaks thereof, and cause rocking of the legs 141 so that the clamps 142 will move toward each other and clamp the button D, raise it slightly to permit the cloth to be inserted under it, and then retain the button in position to be sewn.

Referring to the slot 86 in the arm 85, shown

particularly in Figure 8, when the button D is in position for clamping, the connecting pin 87 of Figure 7 has moved to the lower end of slot 86 and this action completes the action started by the lift lever 30.

The structure 140 to 165 inclusive is retained by a bracket 170 which is shown in Figure 1 and is a conventional attachment of many sewing machines. This bracket 170 arches under the L-shaped bracket 25 and is carried by the work support 27. Downward movement of the slide 148 is effected by a bumper 173 carried by the conventional means for yieldably holding down cloth while being sewn, and which is actuated (lowered) by the foot pedal 38 by way of the rod 39 and lever 30. A retraction coil spring 174 carried at one end by the upper portion of the support 140 and carried at its other end by the slide 148 normally urges the slide upwardly. Normally, the clamps 142 are urged toward each other by the spring 145.

Upon sewing the button D, the pressure upon the slide 148 is released, the legs 141 spread and the clamps 142 release the button and are positioned to again move toward each other to clamp the next button.

The power take off 23 from the drive means C to the hopper 20 and means 21 includes a second pulley 180 on the drive shaft of the motor 35 with a suitable belt 181 from it to a driven pulley 182, which may be upon a shaft 183 carried by a bearing 184 supported by the support bracket 25. The shaft 183 carries a worm gear 185 intermediate its ends. The end of the shaft 183, opposite the pulley end is splined to join the short shaft 59, as in Figure 6 and as previously mentioned. This effects rotation of the worm gear 55.

Housing the worm gear 185 is a gear housing 186 and enclosing a second worm gear 187 meshing with the gear 185. This gear 187 is mounted upon the shaft 98 carrying worm gear 188 at near its other end which is housed in gear housing 189 and meshes with worm gear 190 carried by shaft 191 which extends to and mounts the brush 82. Shaft 191 may be provided with the bearing 192. The end of shaft 98, adjacent its gear 188, mounts the clutch plate 97 as has been described.

From the foregoing, it is apparent that actuation of the foot pedal 38 effects several operations, i. e., it actuates the clutch 95 (which sets in motion the means for positioning the buttons D in positions to be sewn and for delivering them to the clamps 142), and it also effects operation of the clamps 142. However, actuation of the pedal 38, does not affect the operation of the brush 82 nor the means 21 to deliver the buttons right-side-up. On the other hand, the one power take off means 23 operates both means 21 and 22.

The feeding of the buttons D to the hold down means shown particularly in Figures 16 to 24 is timed by the arcuate slot 88 in the rotating disc 89, the pin 87 slidably longitudinally in this slot, and the slot 86 in the depending arm 85. This feeding is timed to take place while the reciprocating portions of the hold down means are at their highest point of travel and while the sliding member 113 is aligned with the hold down means to deliver a button. While the arm 85 is at its lowest point of travel, the link 103 is at its nearest point of travel toward the needle 29, the button D is delivered to the hold down means. The limited length of the slot 88 governs the hold down means so that it moves downward, disengaging the prongs 124 from the button, just before the sliding member 113 moves away from the needle.

It will be noted that, due to the spacer sections 67, the buttons are fed, with spaces between them, rather than in a row. Since the buttons are sewn rapidly, the passageway 80 will not become clogged, the mouth 75 jammed nor a button become positioned half in and half out a depression 66.

The novel attachment may be combined with the conventional sewing machine without making any radical alterations in the construction of the latter and will quickly and efficiently feed buttons, right-side-up, and spaced apart, one from another, in proper position for sewing.

Various changes may be made to the form of the invention herein shown and described, without departing from the spirit of the invention or scope of the claims.

What is claimed is:

1. In a button feeder, for buttons, each having a substantially flat upper face and a convex under face, for association with means for affixing buttons to a support, a hopper; substantially circular walls defining a passageway extending from said hopper; a portion of said walls being integral with said hopper and another portion of said walls being separate from said hopper; means supporting said last-named portion of said walls, for rotation thereof; a gear housing; means securing said gear housing to said fixed wall portion; a row of radially-projecting gear teeth extending around the outer periphery of said rotatable wall portion; a worm gear within said gear housing and meshing with said gear teeth; a discharge way having a mouth; and means for passage of said buttons, one by one, from said passageway to said discharge way, with all the discharged buttons flat-side up, including an outwardly flaring wall extending from the last-named portion of said passageway walls, said outwardly flaring wall having a plurality of spaced-apart concavities, extending from said passageway to said discharge way as they come opposite said mouth of said discharge way upon rotation of said walls.

2. In a button feeder and positioner, for association with a sewing device, having a vertically reciprocating needle, said feeder and positioner including an inclined chute; means for feeding buttons to said chute from the upper end thereof; and means for moving buttons discharged from said chute and positioning the eyes thereof to be entered by said needle, including a slideway in communication with said chute, a sliding member, reciprocable in said slideway, an elongated vibrating member carried by said sliding member at one end of said vibrating member, a headed member pivoted to the other end of said vibrating member, an eye-insertable prong carried by said headed member, a radially extending arm carried by said headed member, an arm extending laterally from said vibrating member, a cam positioned to momentarily contact and raise said second arm and vibrating member, when said second arm reaches said cam upon sliding movement of said sliding member, said cam being disposed along said slideway and adjacent said chute, and an abutment for said first arm, positioned adjacent said chute and on the side thereof of remote from said cam.

3. In a button feeder and positioner, for association with a sewing device, having a vertically reciprocating needle, said feeder and positioner including an inclined chute; means for feeding buttons to said chute from the upper end thereof; and means for moving buttons dis-

charged from said chute and positioning the eyes thereof to be entered by said needle, including a slideway in communication with said chute, a sliding member, reciprocable in said slideway, an elongated vibrating member carried by said sliding member at one end of said vibrating member, a headed member pivoted to the other end of said vibrating member, an eye-insertable prong carried by said headed member, a radially-extending arm carried by said headed member, a retraction coil spring extending longitudinally of said vibrating member, from said headed member to said sliding member, an arm extending laterally from said vibrating member, a cam positioned to momentarily contact and raise said second arm and vibrating member, when said second arm reaches said cam upon sliding movement of said sliding member, said cam being disposed along said slideway and adjacent said chute, and an abutment for said first arm, positioned adjacent said chute and on the side thereof of remote from said cam.

4. In a button feeder and positioner, for association with a sewing device, having a vertically reciprocating needle, said feeder and positioner including an inclined chute; means for feeding buttons to said chute from the upper end thereof; and means for moving buttons discharged from said chute and positioning the eyes thereof to be entered by said needle, including a slideway in communication with said chute, a sliding member, reciprocable in said slideway, an elongated vibrating member carried by said sliding member at one end of said vibrating member, a headed member pivoted to the other end of said vibrating member, an eye-insertable prong carried by said headed member, a radially-extending arm carried by said headed member, a hook secured to and extending upwardly from said sliding member and through said vibrating member, a retraction coil spring extending longitudinally of said vibrating member, secured at one of its ends to said headed member and secured at its other end to said hook, an arm extending laterally from said vibrating member, a cam positioned to momentarily contact and raise said second arm and vibrating member, when said second arm reaches said cam upon sliding movement of said sliding member, said cam being disposed along said slideway and adjacent said chute, and an abutment for said first arm, positioned adjacent said chute and on the side thereof of remote from said cam.

5. In a button feeder and positioner, for association with a sewing device, including a vertically reciprocating needle, said feeder and positioner including an inclined button chute; and means for moving and positioning buttons discharged from said chute and positioning the eyes thereof to be entered by said needle, including an elongated slideway disposed substantially normal to said chute and in communication therewith, said slideway including a base, side walls and inwardly extending flanges at the upper ends of said side walls, a sliding member in said slideway, an elongated member of resilient material carried at one end by said sliding member and extending longitudinally thereof and provided with an arm extending transversely thereof and over one of said flanges, said elongated member having a slot at its free end, a prong-carrying member, including an upper head portion, a neck portion extending into said slot and a base portion provided with button eye-engaging prongs extending downwardly from said base portion, a retraction coil spring extending from said head portion, longitudinally of said elongated member and

11

secured to said sliding member, an arm extending radially from said head portion, a cam extending upwardly from said one of said flanges over which said transversely-extending arm extends and in a position to be contacted by said radially-extending arm, said cam being disposed closely adjacent said chute, and an abutment for said radially-extending arm, positioned adjacent said chute and on the side thereof remote from said cam.

6. In a button feeder and positioner, for association with a sewing device, including a vertically reciprocating needle, said feeder and positioner including an inclined button chute; and means for moving and positioning buttons discharged from said chute and positioning the eyes thereof to be entered by said needle, including an elongated slideway disposed substantially normal to said chute and in communication therewith, said slideway including a base, side walls and inwardly extending flanges at the upper ends of said side walls, a sliding member in said slideway, an elongated member of resilient material carried at one end by said sliding member and extending longitudinally thereof and provided with an arm extending transversely thereof and over one of said flanges, said elongated member having a slot at its free end, a prong-carrying member, including an upper head portion, a neck portion extending into said slot and a base portion provided with button eye-engaging prongs extending downwardly from said base portion, a retraction coil spring extending from said head portion, longitudinally of said elongated member and secured to said sliding member, an arm extending radially from said head portion, a cam extending upwardly from said one of said flanges over which said first arm extends and in a position to be contacted by said first arm, said cam being disposed closely adjacent said chute, an abutment for said second arm, positioned adjacent said chute and on the side

12

thereof remote from said cam, and a button clamp adjacent said abutment and needle.

7. In a button positioner for association with a sewing machine having a vertically reciprocating needle, said positioner including means for orienting the eyes of said button with respect to said needle, means for positioning said button under said needle and means for clamping said button, as oriented and positioned, including a support, a pair of legs pivoted thereto, a clamp at the lower portion of each leg and a cam carried by each leg intermediate its ends, one cam extending toward the other and having a sloping upper surface and a normally substantially horizontally disposed lower surface, a retraction coil spring extending from leg to leg above said clamps, a wedge-shaped member slidably vertically over said support, comprising an upper portion having a pair of sloping lower surfaces engaged by said first-named sloping surfaces, and a lower portion hinged to said upper portion, said lower portion having a foot provided with a pair of substantially horizontally-disposed surfaces engaged by said first-named horizontally disposed surfaces, and a rounded surface, and resilient means, normally urging said lower portion against said support and in the same vertical plane as the vertical plane of said upper portion.

WILLIAM R. McDANIEL.
